UNITED STATES PATENT OFFICE.

WILLIAM G. KENDALL, OF NEWARK, NEW JERSEY.

VANITY-CASE.

1,342,116.

Specification of Letters Patent.

Patented June 1, 1920.

Application filed July 22, 1918. Serial No. 246,214.

To all whom it may concern:

Be it known that I, WILLIAM G. KENDALL, a citizen of the United States, residing at Newark, in the county of Essex and State 5 of New Jersey, have invented certain new and useful Improvements in Vanity-Cases, of which the following is a specification.

This invention relates to vanity cases and more particularly to that type which 10 are designed to contain two kinds of cosmetics as for example a face powder cake and a rouge cake, although the invention is not limited in its usefulness to the housing of powder cakes as other forms of cosmetics might be equally as well arranged 15 within the case. Where two dissimilar cosmetics are to be housed in a single container as in the instance of the present invention, it is, of course, desirable that they 20 be kept separated so that they cannot become comingled. The present invention therefore has as one of its objects to so construct the case that the two cosmetics, as for example the face powder cake and the rouge 25 cake, will be so housed in separate compartments as to prevent any loose powder from either cake reaching the surface of the other cake.

Another object of the invention is to so 30 construct the article that when the same is closed, one cosmetic compartment will cover and act as a closure for the other compartment, the cover for the case as a whole, in turn serving to cover and close the first- 35 mentioned compartment, so that when the case is completely closed both compartments will be closed in a substantially air-tight manner so that the cosmetics may retain their fragrance and will not be subject to 40 deterioration.

Another object of the invention is to so construct the case that access to the most frequently employed cosmetic may be readily had by merely opening the lid of the 45 case and without exposing the other cosmetic or opening the compartment or tray in which it is contained.

A further object of the invention is to utilize the lid of the case as a means for 50 holding the two sections of the case in relatively closed position and so that they cannot be swung open until the lid itself has been swung upwardly to open position.

A further object of the invention is to 55 provide for the assemblage and securing together of all of the members and elements

of the device without the employment of solder, rivets, or any individual fastening means, thus rendering the article less expensive to manufacture and capable of more 60 ready and expeditious assemblage of its parts.

Another object of the invention is to so construct the case that when fully opened, both cosmetics will be exposed for use and 65 the case as a whole may be placed in upright position upon any suitable supporting surface, with the mirror within the lid of the case also in upright position so as to add greatly to the convenience of using the 70 article.

In the accompanying drawings:

Figure 1 is a perspective view of the case embodying the present invention, the same being shown closed; 75

Fig. 2 is a similar view showing the case fully opened;

Fig. 3 is a top plan view of the case in open position;

Fig. 4 is a group perspective view illustrating the various parts of the case disassembled. 80

Generally speaking, the body of the case is substantially in the form of a hollow cylinder closed at its lower end and divided 85 from end to end diametrically into two halves or sections. However, the said body of the case may be other than of cylindrical form if desired. In the drawings the said body of the case is indicated in general by 90 the numeral 1 and the same comprises two sections one of which is indicated by the numeral 2 and the other by the numeral 3. Each of these sections, of course, includes a substantially semi-cylindrical wall 4 and a 95 substantially semi-circular bottom wall 5 and when the sections are closed upon the hinge which connects them as will be presently explained, the edges of the walls 4 and 5 of the two sections will abut and match 100 to form the body of the shape above mentioned. The sections 2 and 3 are formed respectively at one vertical edge of the wall 4, with pintle lugs 6, which when the sections are assembled, interdigitate, and a pintle 7 is fitted through the matching lugs so as to hingedly connect together the said sections. 105

The upper edge portions of the walls 4 of the sections 2 and 3 are either struck in 110 to provide or are provided each with a semi-anular rim 8 extending around the interior

of the said wall 4, and when the sections are closed, the ends of the two rim portions, of course, register so as to form the complete rim. The lid of the case as a whole is indicated in general by the numeral 9 and the same includes a flat body or top 10 and a depending circumscribing flange or rim 11 which, when the lid is in closed position, is designed to fit down over the rim 8 and frictionally fit the same so as to not only retain the lid in closed position but also lock the two sections of the body of the case against swinging movement away from each other. In order to hingedly connect the lid with the body, the section 3 of the body is provided in its rim 8 with a slot 12, the formation of which slot results in a relatively narrow portion lying between the slot and the upper edge of the rim and constituting a pintle indicated by the numeral 13. The flange 11 of the lid 9 is provided at a point in its circumference with an extension 14 which is fitted through the slot 12 and bent to substantially sleeve-like form so as to surround the pintle portion 13. In this manner without the employment of any separate and distinct hinge required to be riveted or otherwise secured to the section 3 and lid 9, the said lid may be readily and conveniently hingedly connected with the said section. At a point preferably diametrically opposite the extension 14, the flange or rim 11 of the lid 9 is preferably provided with an outwardly projecting finger-piece 15 by means of which it may be readily swung to open position. It is preferable that a mirror 16 be arranged within the lid 9 as is usual in articles of this general type.

In the illustrated embodiment of the invention, the case is designed to house a pad containing a cake of face powder and a pad containing a cake of rouge, and also two powder puffs by means of which the cosmetics may be applied. In order to house the cosmetics and the applying puffs, the present invention contemplates the provision of two trays, one carried in the lower portion of the section 2 and the other in the upper portion of the section 3. The first-mentioned tray is indicated by the numeral 17 and the second-mentioned tray by the numeral 18. The tray 17 is relatively deep and comprises a cylindrical wall 19 and a bottom 20, and the upper edge of the wall 19 is formed at intervals in one half of its circumference with upstanding tongues 21 which, in the assemblage of the tray 17 with the section 2, are bent outwardly and fitted through slots 22 formed in the wall 4 of the section 2, the tongues being then bent upwardly as clearly shown in Fig. 2 of the drawings so as to secure the tray in place. The bottom 20 of the tray rests upon the bottom 5 of the section 2, the said bottom 5 extending, of course, beneath one-half

of the bottom 20 of the tray, and one-half of the circumference of the wall 19 of the tray is disposed snugly against the inner face of the wall 4 of the said section 2. A pad 23 containing a tablet or cake 24 of rouge is disposed and held by friction in the bottom of the tray 17 and a powder puff 25 is housed within the upper portion of said tray 17 and rests upon the said cake 24 as shown in Fig. 2 of the drawings. As the tray 17 is relatively deep, it will completely house both the cosmetic and the powder puff, and it occupies substantially the lower half of the casing when the sections of the casing are closed together. 80

The tray 18 is relatively shallow and includes a cylindrical wall 26 and a bottom 27, and as in the case of the tray 17, the upper edge of the wall 26 is provided with upstanding tongues 28 corresponding to the tongue 21 and adapted to be bent outwardly and inserted through slots or openings 29 formed in the upper portion of the wall 4 of the section 3, the ends of these tongues after such insertion through the slots, being 90 bent downwardly as shown in Fig. 1 of the drawings. The numeral 30 indicates a pad containing a cake 31 of face powder, and the numeral 32 indicates a powder puff for employment in connection with the cake 31. 95 The pad 30 is disposed within the bottom of the tray 18 and the said pad and cake are completely housed within the said tray. The upper edge of the wall 26 of the tray 18 does not, however, extend to the extreme 100 upper edge of the body section 3 but, on the other hand, terminates beneath and preferably abuts against the shoulder formed by providing the rim 8. Thus what the tray 18 lacks in height as compared with the tray 105 17 is supplied by the rim 8 which, of course, completely surrounds the top of the tray 18 when the body sections of the case are closed together, and thus the tray is given sufficient depth to properly house the puff 32. 110

It will be apparent from the foregoing description of the invention and from inspection of the drawings that ready access may be had to the cosmetic which is most frequently employed, namely, the face powder 115 cake 31, by merely swinging up the lid 9 to the vertical position shown in Fig. 2 without, however, swinging apart the sections 2 and 3 of the body of the case. Thus when it is desired to use only this particular 120 cosmetic, this may be done without opening or exposing the interior of the tray 17. Of course, when it is desired to gain access to the rouge cake, the two sections 2 and 3 will be swung apart upon their hinge in 125 the manner shown in Fig. 2 of the drawings, and with the sections thus positioned, the article as a whole may be placed upon a dresser top or any other suitable support and be thus very conveniently employed in- 130

asmuch as both cosmetics are exposed for use and the mirror within the lid is in upright position immediately behind the tray 18.

5 Having thus described the invention, what is claimed as new is:

In an article of the class described, a casing comprising two substantially semi-cylindrical sections each having a bottom and 10 each being open at its top, each section at the upper edge of its wall being provided with a rim, hinge connection between the walls at one side whereby when the sections

are swung together the chordal edges of their bottoms will meet and the ends of their 15 rims will also meet, a tray secured within one section and resting upon the bottom thereof, a tray secured within the upper portion of the other section and arranged to lie above the first mentioned tray when the sections are closed, and a lid for closing the top of the casing hinged to the rim of one section and arranged in closed position to fit about the rims of the two sections.

In testimony whereof I affix my signature. 25
WILLIAM G. KENDALL. [L.S.]
